US0D1029082S

(12) **United States Design Patent** (10) **Patent No.:** **US D1,029,082 S**
(45) **Date of Patent:** **** May 28, 2024**

(54) **SMART GLASSES**

(71) Applicant: **Falcon Innovations Technology (Shenzhen) Co., Ltd**, Shenzhen (CN)

(72) Inventors: **Bin Zheng**, Shenzhen (CN); **Mingjie Wang**, Shenzhen (CN)

(73) Assignee: **Falcon Innovations Technology (Shenzhen) Co., Ltd.**, Shenzhen (CN)

(**) Term: **15 Years**

(21) Appl. No.: **35/517,529**

(22) Filed: **May 22, 2023**

(80) **Hague Agreement Data**

Int. Filing Date: **May 22, 2023**

Int. Reg. No.: **DM/229426**

Int. Reg. Date: **May 22, 2023**

Int. Reg. Pub. Date: **Jun. 16, 2023**

(30) **Foreign Application Priority Data**

Dec. 8, 2022 (CN) 202230823498.7

(51) **LOC (14) Cl.** **16-06**

(52) **U.S. Cl.**

USPC **D16/309**

(57) **CLAIM**

The ornamental design for smart glasses, as shown and described.

DESCRIPTION

1. Smart glasses

1.1 : Front

1.2 : Back

1.3 : Left

1.4 : Right

1.5 : Top

1.6 : Bottom

1.7 : Perspective

1.8 : Perspective

(Continued)

The design is smart glasses used for augmented reality technology; reproductions 1.1 to 1.8 are drawings showing an embodiment of the smart glasses.

1 Claim, 8 Drawing Sheets
